UNITED STATES PATENT OFFICE.

GEORGE W. ELSEY, OF ANDERSON, INDIANA, ASSIGNOR TO GENERAL MOTORS CORPORATION, A CORPORATION OF DELAWARE.

ENGINE-STARTING APPARATUS.

Application filed May 1, 1924. Serial No. 710,470.

To all whom it may concern:

Be it known that I, GEORGE W. ELSEY, a citizen of the United States of America, residing at Anderson, county of Madison, and 5 State of Indiana, have invented certain new and useful Improvements in Engine-Starting Apparatus, of which the following is a full, clear, and exact description.

This invention relates to starting apparatus for internal combustion engines, particularly, to a type of apparatus including an electric motor operating a gear which is movable axially into engagement with a gear connected with the engine, such as the 15 engine flywheel gear.

Among the objects of the invention are the connecting of the motor gear with the engine gear and the operating the motor by manual operation; for example, by means 20 of a starting lever, and the demeshing of the motor gear from the engine gear automatically when the engine starts, regardless of whether the starting lever is still maintained in engine-starting position.

25 In order to accomplish these objects the invention provides means responsive to the operation of the starting motor for disconnecting the starting motor pedal from a device which engages the motor gear to shift it axially into engagement with the flywheel gear. The motor gear is connected with the motor shaft by a spiral spline or screw thread. Consequently, when the engine becomes self-operative, the motor gear will be 30 automatically demeshed from the engine gear, altho the starting motor pedal may not yet be released by the operator.

Further objects and advantages of the 40 present invention will be apparent from the following description, reference being made to the accompanying drawings, wherein a preferred form of embodiment of the present invention is clearly shown.

In the drawings:

45 Fig. 1 is a fragmentary side view partly in section, of a starting motor and gearing, including a form of the invention, the apparatus being in normal or inoperative condition.

50 Fig. 2 is a view similar to Fig. 1, showing the apparatus in condition for cranking the engine.

Referring to the drawings: 20 designates a gear housing including a bracket 21 for

supporting the housing upon the frame of an 55 engine, not shown, but represented in the drawings by an engine flywheel gear 22. The housing 20 supports a motor field frame 23. By means of a bearing (not shown), the frame supports the motor shaft 24 having 60 one end journaled at 25 in the gear housing 20. The shaft 24 is provided with a spirally-splined or threaded portion 26, which engages an internally-threaded motor gear 27 carrying a flanged washer 28 projecting beyond the periphery of the gear.

The motion-transmitting device for shifting gear 27 endwise into engagement with the gear 22 includes a bifurcated lever 29, pivoted upon a shaft 30 carried by housing 70 20, the bifurcations of lever 29 being connected by a yoke 31 and the ends thereof being rounded at 32 to engage a grooved collar 33. Between collar 33 and the end 34 of the armature core there is located a spacer 75 35. A spring 36, coiled around the shaft 30 has one end 37 bearing against the gear housing 20, and the other end 38 bearing against the yoke 31. Between the grooved collar 33 and the gear 27 there is located a 80 spring 40 in an initial state of compression by means of spring housing members 41 and 42, which limit the separation of members 33 and 27. Housing member 41 is attached as shown in Fig. 1 to the collar 33 and is 85 provided with a flange 43 connected with a flange 45 of the member 42 by lugs 44 integral with flange 45 and bent around flange 43. Member 42 is provided with an opening 46, which is large enough to clear 90 the motor gear 27 but is smaller in diameter than the external diameter of the washer 28.

The manually operable means for moving the motion-transmitting device, includes a lever 50 pivoted upon the shaft 30 and carrying an adjustable screw 51 adapted to engage the plunger 52 of a motor-operating switch enclosed within a housing 53. One terminal of the switch for connection with a current source is shown at 54 and the other 100 terminal not shown is connected with the motor field circuit. The lever 50 is operated by a rod 55 carrying a pedal 56 located in convenient reach of the driver.

The means for connecting the lever 50 105 with a gear shifting lever 29, includes a pawl 60 pivoted upon a stud 61 carried by lever 50. The pawl engages a notch 62 in the

lever 29 and is normally held in this position by means of a spring 63 coiled around the stud 61 and having one end 64 bearing against an ear 65 of the pawl 60, said ear 5 being at right angles to the main portion of the pawl 60. The other end 66 of spring 63 bears against a stud 67 on lever 50.

The motor field frame 23 supports a bracket 70 providing a guide for a ¹⁰ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ²²⁰ ²²⁵ ²³⁰ 2. Engine starting apparatus comprising in combination, an engine having a gear; a motor and gear driven thereby; a motion-transmitting member for meshing the motor gear with the engine gear; a manually operable member for actuating the motion-transmitting member; means including a spring released for operation when the motor starts for automatically disconnecting said members; and automatic means for demeshing the motor gear when the engine starts. 70
3. Engine starting apparatus comprising in combination, an engine having a gear; a motor and gear driven thereby; a motion-transmitting lever for meshing the motor gear with the engine gear; a manually operable lever for actuating the first lever; means normally connecting said levers; a device released for operation when the motor starts for moving the connecting means to disconnect said levers; and automatic means for demeshing the motor gear when the engine starts. 75
4. Engine starting apparatus comprising in combination, an engine having a gear; a motor and gear driven thereby; a motion-transmitting lever for meshing the motor gear with the engine gear; a manually operable lever for actuating the first lever; a pawl pivoted on the second lever and normally engaging the first lever; a spring located in the path of movement of the pawl and released when the motor starts for moving the pawl out of engagement with the motion-transmitting lever; and automatic means for demeshing the motor gear when the engine starts. 80
5. Engine starting apparatus comprising in combination, an engine having a gear; a motor and shaft driven thereby; a motor gear spirally splined to said shaft; manually operable means for entering the motor gear into mesh with the engine gear and for causing the motor to operate the motor gear whereby the motor will actuate the motor gear into full engagement with the engine gear and crank the engine; and means, released by the relieving of the operating pressure delivered to the motor gear by the manual means when the motor starts, for automatically disconnecting the manual means from the gear, whereby the motor gear will be automatically demeshed from the engine gear when the engine becomes self-operative, regardless of manipulation of the manual means. 85
6. Engine starting apparatus comprising, in combination, an engine having a gear; a motor and shaft driven thereby; a motor gear; manual means for entering the motor gear into mesh with the engine gear and for causing the motor to operate the shaft; means connecting the shaft and motor gear and adapted to cause the motor gear to be moved by motor operation, independently 90
7. Engine starting apparatus comprising, in combination, an engine having a gear; a motor and gear driven thereby; a motion-transmitting member for meshing the motor gear with the engine gear; a manually operable member for actuating the motion-transmitting member; means responsive to operation of the motor for completely meshing the motor gear with the engine gear, and responsive to the self operation of the engine for demeshing the motor gear from the engine gear; and means for disconnecting said members in response to movement of the motor gear into mesh with the engine gear 95
8. Engine starting apparatus comprising, in combination, an engine having a gear; a motor and gear driven thereby; a motion-transmitting member for meshing the motor gear with the engine gear; a manually operable member for actuating the motion-transmitting member; a connector for said members normally located so as to connect the members; a spring operated part for engaging the connector and tending to move the connector out of engagement with one of the members but restrained from so doing by reason of the transmission of force from one member to the other through said connector; means responsive to the operation of the motor for relieving the force transmitted by the connector whereby the spring is released to cause the connector to be disconnected from one of the members; and automatic means for demeshing the motor gear when the engine starts. 100
9. Engine starting apparatus comprising, in combination, an engine having a gear; a motor and gear driven thereby; a motion-transmitting member for meshing the motor gear with the engine gear; a manually operable member for actuating the motion-transmitting member; means responsive to operation of the motor for completely meshing the motor gear with the engine gear, and responsive to the self operation of the engine for demeshing the motor gear from the engine gear; a connector for said members normally located so as to connect the members; a spring operated part for engaging the connector and tending to move the connector out of engagement with one of the members but restrained from so doing, by reason of the transmission of force from 105

- 115
- 120
- 125
- 130

one member to the other through said connector; and means responsive to movement of the motor gear into mesh with the engine gear due to operation of the motor for releasing the force transmitted by the connector whereby the spring is released to cause the connector to be disconnected from one of said members.

10. Engine starting apparatus comprising, in combination, an engine having a gear; a motor; a spirally splined shaft driven thereby; a motor gear mounted upon the shaft and having a bore provided with spiral grooves receiving the shaft splines; 15 a shifting collar connected with the motor gear; a pivoted shafting lever cooperating with the collar; a pedal operated lever pivot-

ally coaxially with the shifting lever; a pawl connected with the pedal lever and normally engaging a part of the shifting lever; and a spring pressed member located in the path of movement of the pawl as the levers are operated for urging the pawl out of engagement with the shifting lever, the pawl and shifting lever part having co-operating engaging surfaces so shaped that engagement of the pawl and shifting lever is maintained until the operation of the motor causes the motor gear to be moved into complete engagement with the engine gear.

In testimony whereof I hereto affix my signature.

GEORGE W. ELSEY
